(57) **CLAIM**

I claim the ornamental design for an atrium for an educational learning facility, as shown and described.

DESCRIPTION

FIG. 1 illustrates a plan view of an atrium for an educational learning facility of my new design;

FIG. 2 illustrates an upper right perspective view thereof;

FIG. 3 illustrates a front elevational view thereof, the rear elevational view being a mirror image; and,

FIG. 4 illustrates a right elevational view thereof, the left elevational view being a mirror image.

The broken lines shown on the top, inner edge of FIGS. 1 and 2 illustrate boundaries of the atrium for an educational learning facility that form no part of the claimed design. The additional broken lines shown in FIG. 1 illustrate environment and form no part of the claimed design.
